ATTORNEYS

UNITED STATES PATENT OFFICE.

GEORGE ALT, OF EVANSVILLE, INDIANA.

ANNUNCIATOR.

1,236,647.

Specification of Letters Patent. Patented Aug. 14, 1917.

Application filed August 14, 1915. Serial No. 45,596.

To all whom it may concern:

Be it known that I, GEORGE ALT, a citizen of the United States, and a resident of Evansville, in the county of Vanderburg and State of Indiana, have invented a new and useful Improvement in Annunciators, of which the following is a specification.

My invention is an improvement in annunciators, and the invention has for its object to provide a device of the character specified, for use in moving picture and other darkened theaters for indicating the number and the location of vacant seats.

In the drawings:—

15 Figure 1 is a perspective view of the annunciator,

Fig. 2 is a section on the line 2—2 of Fig. 1, looking in the direction of the arrows adjacent to the line, and

20 Fig. 3 is a diagrammatic view of the wiring.

The present embodiment of the invention comprises a substantially rectangular casing 1, having an opening 2 in one of its side walls, and the opening is normally closed by a sheet 3 of glass or the like, the said sheet extending at one end through a slot 4, in the end of the casing to permit the sheet to be withdrawn or replaced.

25 30 A support consisting of horizontal portions 6, and a vertical portion 5 is arranged in the casing, the said support extending from one end to the other and from the rear wall to near the front wall, and the vertical

35 portion 5 is spaced apart from the front wall. This support if desired, may be a vertical partition extending longitudinally of the box and it is a support for lights, to be later described.

40 45 Partitions 7 are arranged transversely of the space between the vertical portion 5 of the support and the sheet 3, the said partitions dividing this space in the present instance into four compartments. In each of these compartments an illuminating device, in the present instance, an electric light 8, is arranged, the said lights being secured to the vertical portion of the support 5—6.

The sheet 3 is provided with a series of indicating characters 9, the said characters being numerals in the present instance, and arranged consecutively, designating the compartments in front of which the numerals are arranged.

55 A tubular extension 10 extends from the

rear of the casing, and from the center, and the outer end of this extension is normally closed by a door 11, which is hinged to the extension at 12, and is provided with spring latch mechanism 13, for holding the door 60 closed. A switch plate 14 is arranged on the tubular extension, and this plate has four push buttons 15, which are connected to the respective lights in a manner to be presently described. The push buttons 15 are 65 connected to the lights, and to one or more dry cells indicated at 16, which are arranged in the tubular extension.

The arrangement of the circuits is shown in Fig. 3, wherein the battery 16 has lead 70 wires 17 and 18, connected with the respective terminals of the battery. The lights 8 are arranged in parallel between these lead wires, each light being interposed in the length of a lead wire 19, in which the push 75 button 15 pertaining thereto is also interposed.

It will be evident that when any push button is depressed, the light pertaining thereto will be connected to the battery to ignite the 80 same and that partition in which the particular light is placed will be illuminated to show the number in front of the light.

While but four lights and four numbers are shown, it will be evident that any desired 85 number might be used. The usher grasps the annunciator by the tubular extension 10, this extension forming a convenient handle for the purpose.

I claim:—

1. A hand annunciator, comprising a casing having one side open and having a sheet of transparent material covering the said open side, said casing having a support in rear of the sheet and a series of transverse 95 partitions between the support and the sheet and separating the casing into compartments, an electric light in each compartment, the sheet having numerals at the compartments, a tubular extension at the rear of the 100 casing and communicating therewith, a switch plate provided with a push button for each lamp on the extension, a cover closing the outer end of the extension, said extension being adapted to contain a battery, 105 and said battery being connected to the push buttons and to the lamps.

2. A hand annunciator, comprising a casing having one side open and having a sheet of transparent material covering the said 110

open side, said casing having a support in rear of the sheet and a series of transverse partitions between the support and the sheet and separating the casing into compartments, an electric light in each compartment, the sheet having numerals at the compartments, a chambered handle connected with

the casing and adapted to contain a battery, and a switch plate on the handle and connected with the battery and the lamps.
